FLUME DIVIDER

Joseph D. Coffee, Pueblo, Colo.

Application September 3, 1946, Serial No. 694,634

6 Claims. (Cl. 61—14)

1

This invention relates to flume dividing boxes or weirs, and more particularly to flume dividing boxes or weirs which are adapted to dividing a stream of water flowing in the flume, into two or more equal parts, or predetermined proportions.

Heretofore the water flowing in flumes has been divided either by a side gate take-off, or by natural gates placed in the flume, but it has been necessary to measure not only the amount of water flowing down the flumes, but also the amount of water flowing down the side or take-off ditches. Needless to say, many inaccuracies are involved in the operation of such a divider, among which are the accumulations of silt and debris, which settle in and around such boxes and impair their accuracy so that too much attention must be paid to the measurement. Also, when the water rights of those who are entitled to receive water from the ditch, vary in predetermined proportions, it is often difficult to calculate the exact amount of water received by each water right owner, without undue time and effort being consumed in measuring the flow down the take-off ditches.

The flume divider or weir of this invention is particularly applicable to instances in which the water right owners are entitled to a predetermined proportion of the water flowing down the ditch, i. e., each of two owners may be entitled to 50% of the water, or each of three owners may be entitled to 33 1/3% of the water, or any number of owners may be entitled to any predetermined proportion of the water. The divider of this invention keeps the proportional division accurate due to prevention of the usual silt and trash accumulations generally prevalent in an open ditch or flume.

In accordance with this invention, a flume divider is constructed with a crest disposed at the top of a relatively steep upward slope and receives water directly from the ditch, imparting an upward component thereto which keeps the upward slope swept clear of silt and debris. On the downstream side of the crest is a downwardly sloping section having substantial parallel side walls, which produce a flow of even depth across the width of the slope. At the lower end of the slope, there is a trough sufficiently deep to produce a fall which releases any entrained air, thus insuring that, after the water passes over the edge of the fall, its depth and rate of flow will be substantially uniform across the width of the weir. Dividing plates, extending vertically in the direction of the flow, and up to the edge of

2

the fall, divide the uniform depth of water flowing over the fall, into predetermined proportions, in accordance with the distance between two dividing plates, or between a dividing plate and the side wall of the weir. A single dividing plate at the center of the fall will divide the flow into two equal parts, while two dividing plates, spaced one-third of the way across the edge of the fall, will divide the flow into three equal parts. It will be understood, of course, that the position of the plates may be varied in accordance with the proportion of the water which each user is entitled to receive.

Flume dividers or weirs, constructed in accordance with the above principles of this invention, are illustrated in the accompanying drawing, in which:

Fig. 1 is a top plan view of a flume divider or weir constructed in accordance with this invention, and adapted to guide the flow of water in a flume or ditch into two equal parts;

Fig. 2 is a top plan view of a flume divider or weir adapted to divide the flow of water into three equal parts;

Fig. 3 is a longitudinal vertical section of the flume divider of Fig. 2, taken along line 3—3 thereof;

Fig. 4 is a transverse vertical section looking upstream and taken along line 4—4 of Fig. 3; and

Fig. 5 is a transverse vertical section looking downstream and taken along 5—5 of Fig. 3.

The flume divider of Fig. 1 and Fig. 2 comprises an upstream apron 10 which slants upwardly at a relatively sharp angle to a crest 11,

and provided with converging side walls 12, which merge with parallel side walls 13, a substantial distance upstream from crest 11. The ditch 14 may be provided with earthen walls 15 which lap over the side walls 12, as in Figs. 2 and 5, so as to prevent any by-passing and to minimize erosion at the point of the flume divider.

Immediately downstream of crest 11 is a downwardly sloping apron 16 which extends between parallel side walls 13 to an edge 17 of a transverse vertical wall 18, which provides a fall for the water into a trough 19, from which continuation ditches 20 of Fig. 1, and 21 of Fig. 2, and/or lateral ditches 22 of Fig. 2 lead.

One vertical longitudinal dividing plate 23, as in Fig. 1, or two vertical longitudinal dividing plates 24, as in Figs. 2 to 4, inclusive, or any desired number of dividing plates in accordance with the number of proportions into which the water is to be divided, are installed in trough 19. The upper edge of the dividing plates 22, 23 and

24 are level with the edge 17 of vertical wall 18, although they may extend slightly above the level of edge 17, if desired. In order to permit the escape of air underneath the water falling over edge 17, diverging walls 25 of Fig. 1, or laterally extending side walls 26 of Fig. 2, provide a greater width below wall 18, than above.

The flume divider of this invention is normally constructed of concrete and angle irons, although any other suitable materials may be used where desired. Thus, an angle iron 28 may be installed at crest 11, and angle iron 29 at edge 17 of the vertical wall 18, as is more clearly evident from Fig. 3. Also, angle irons 30 may be provided at the downstream edges of substantially parallel side walls 13, as in Figs. 2 and 4. Dividing plates 23, 24 and 25 may be mounted in concrete pillars 31, as in Fig. 4, to maintain the same in position. Preferably, the side walls 12 and 13 diverge slightly outwardly, so that the water that might remain in the flume or ditch, in freezing will not tend to break the concrete, but the ice will merely tend to lift itself out of the flume.

The dividing plate 23 of Fig. 1 is adapted to divide the stream flowing down sloping apron 16 into two equal parts, and a portion of the continuation ditches 20 may also be made of concrete, with a center, wedge-shaped pillar 32 extending to the full height of the ditch walls, and adapted to minimize erosion of the ditch walls. Similarly, pillars 31 may be provided between the continuation ditch 21 and the lateral ditches 22 of Fig. 2. The diverging side walls 25 and the sides of pillar 32 of Fig. 1, as well as the lateral side walls 26 and the sides of pillars 31 of Fig. 2, also preferably diverge upwardly, to prevent damage to the concrete by freezing.

While the flume dividers of this invention accurately divide the water into predetermined proportions, it frequently will be desired to measure the ditch flow in order to utilize the allotted flow to best advantage, and for this purpose, a gauge 34, adapted to indicate the depth of water flowing between substantially parallel side walls 13, and down apron 16, may be installed on one side wall 13, as in Figs. 1 and 3. In addition, each of the diverging side walls 25, as in Fig. 1, may be provided with a gauge 35, adapted to indicate the depth of water in the continuation ditches 20. Similar gauges may be placed on the side walls of the continuation ditch 21 and lateral ditches 22 of Fig. 2, if desired.

From the foregoing, it will be apparent that the flume divider's use fulfills to a marked degree the requirements and objects hereinbefore set forth. The upwardly sloping apron 16 tends to equalize the rate of flow between surface and sub-surface currents, as well as preventing an accumulation of silt at crest 11, and the converging side walls 12 assist in the production of a uniform flow of water across the crest 11. The downstream spacing of crest 11 from the upstream intake and the arrangement of substantially parallel side walls 13 contribute considerably to the uniformity of flow, as the apron 16 extends upwardly over a considerable portion of the distance between substantially parallel side walls 13 and exerts its greatest leveling influence in this stretch. The slope of downstream apron 16 need not be great, and a slope of one foot per inch will be sufficient for most cases. The position of the dividing plates on the downstream side of the vertical wall 18, and the depth of trough 19 insures that the dividing plates will be oper-

ating on a falling stream of water which remains substantially uniform in depth across the width of the weir.

From the foregoing description, it will be apparent that the divider box of the present invention is positive in its action under varying conditions. The substantial angular elevation of the bottom in the intake portion coupled with the narrowing of the intake provided by the arrangement of walls 12 interrupts the normal flow of the incoming stream regardless of its depth. Thus, any tendency of the water to channel and run faster and in greater volume in a given portion of the stream is offset by the narrowing of said stream and the elevation of its bottom flow at reducing velocity.

At the crest, the flow is uniform throughout the extent of the stream and to prevent any silt deposit or similar condition which might produce an unequal flow beyond the crest, the apron 16 declines from said crest at a sufficient angle to produce an accelerated rate of flow which keeps this portion of the divider box swept clean of debris. With the flow-directing contour provided, the distance from the crest 11 to the edge 17 is too short for any flow irregularities to develop, and consequently, a uniform distribution of flow is maintained at the fall.

The expanding area of the side walls and the declining bottom arrangement in the dividing or discharge portion of the divider box serves to prevent any false level condition that otherwise might result from entrainment of air, while the slope of the bottom in this portion serves to prevent any accumulation of silt or other debris which might produce inaccurate levels at the division points. Finally, the depth and area of trough 19 in relation to the volume of the stream flowing down apron 16 provides overcapacity volume for any such flow that may be delivered thereto. By locating the division members at substantially the same elevation as the top of wall 18, an accurate distribution is insured at all times, regardless of variations in flow.

Although two embodiments of this invention have been described with particularity, it will be evident that other embodiments may exist and that various changes may be made, all without departing from the spirit and scope of this invention as defined in the hereunto appended claims.

What I claim and desire to secure by Letters Patent is:

1. A divider box for flumes comprising an intake portion having an upwardly sloping bottom, an intermediate portion having a substantially level bottom, and a discharge portion having a bottom at a lower level than the bottom of said intermediate portion, a vertical wall connecting the bottom of said intermediate portion and the bottom of said discharge portion, side walls on said bottom portions, the side walls converging in said intake portion, continuing parallel in said intermediate portion, and parallel but at a greater distance apart in said discharge portion, and divider members in said discharge portion dividing the flow over the crest of said vertical wall.

2. A divider box for flumes comprising a bottom, said bottom rising sharply in a downstream direction to a crest, falling on a slight decline a short distance, breaking sharply to form a vertical wall and continuing from the base of said wall, side walls converging to a point slightly upstream from the crest of said sharply rising

bottom portion for increasing the rate of flow over said crest, diverging side walls downstream from the vertical wall, and a permanently supported divider member having its top edge at approximately the elevation of the top edge of the vertical wall extending from the vertical wall in the direction of fluid flow for dividing said flow into two channels.

3. A divider box for flumes comprising an intake portion having an upwardly sloping bottom, an intermediate portion having a substantially level bottom, and a discharge portion having a bottom at a lower level than the bottom of said intermediate portion, a vertical wall connecting the bottom of said intermediate portion and the bottom of said discharge portion, side walls on said bottom portions, the side walls converging in said intake portion, continuing parallel in said intermediate portion, and at a greater distance apart in said discharge portion, and divider members in said discharge portion dividing the flow over the crest of said vertical wall.

4. A divider box for flumes comprising an intake portion having an upwardly sloping bottom, an intermediate portion having a substantially level bottom, and a discharge portion having a bottom at a lower level than the bottom of said intermediate portion, a vertical wall connecting the bottom of said intermediate portion and the bottom of said discharge portion, side walls on said bottom portions, the side walls converging in said intake portion, continuing parallel in said intermediate portion, and at a greater distance apart in said discharge portion, and divider members in said discharge portion adjacent said vertical wall, said divider members having an upwardly disposed edge to divide a vertically falling flow of liquid.

5. A divider box for flumes comprising a bottom, said bottom rising sharply in a downstream direction to a crest, falling on a slight

decline a short distance, breaking sharply to form a substantially vertical wall and continuing from the base of said wall, outwardly sloping side walls above said bottom, said side walls converging to a point slightly upstream from the crest of said sharply rising bottom portion for increasing the rate of flow over said crest, diverging side walls downstream from the vertical wall and a permanently supported divider member having its top edge at approximately the elevation of the top edge of the vertical wall extending from the vertical wall in the direction of fluid flow for dividing a substantially vertical flow of liquid into a plurality of channels.

10 6. A divider box for flumes comprising a bottom, said bottom rising sharply in a downstream direction to a crest, falling on a slight decline a short distance, breaking sharply to form a substantially vertical wall and continuing from the base of said wall, outwardly sloping side walls above said bottom, said side walls converging to a point slightly upstream from the crest of said sharply rising bottom portion for increasing the rate of flow over said crest, side walls at a greater distance apart downstream from the vertical wall and a permanently supported divider member having its top edge at approximately the elevation of the top edge of the vertical wall extending from the vertical wall in the direction of fluid flow for dividing a substantially vertical flow of liquid into a plurality of channels.
